UNITED STATES PATENT OFFICE.

THEODORE J. A. VANDERLOO, OF PHILADELPHIA, PENNSYLVANIA, ASSIGNOR
TO THE PHILADELPHIA HARDWARE AND MALLEABLE IRON WORKS, OF
PENNSYLVANIA.

DESIGN FOR A REGISTER OR VENTILATOR PLATE.

SPECIFICATION forming part of Design No. 31,446, dated August 22, 1899.

Application filed July 26, 1899. Serial No. 725,197. Term of patent 14 years.

To all whom it may concern.

Be it known that I, THEODORE J. A. VANDERLOO, a citizen of the United States, residing in the city and county of Philadelphia, State of Pennsylvania, have invented and produced a new and original Design for Register or Ventilator Plates, of which the following is a specification, reference being had to the accompanying drawings, forming part thereof.

10 The leading feature of my design for a register or ventilator plate is a central rosette, concentric rings with segmental-shaped figures around the same, a field of segmental shaped figures surrounding said rings, and a border of arches.

15 Figure 1 represents a face view of a register and ventilator plate embodying my design. Fig. 2 represents a section thereof on line $x x$, Fig. 1.

20 In the drawings, A designates a register or ventilator plate consisting of the central ro-

sette B, the concentric rings C, the segments D E F G, and the arches H.

The segments D overlap each other and form a circular figure around the rosette B. 25 The segments E and F are disposed within the concentric rings C, and the segments G compose a field around the outer ring C, said segments being in pairs, producing elliptical-shaped figures. 30

The arches H constitute the border of the plate and surround the field of segments G.

Having thus described my invention, what I claim as new, and desire to secure by Letters Patent, is—

35 The design for a register and ventilator plate substantially as shown and described.

THEODORE J. A. VANDERLOO.
